STUFFED DOLL

Hazel Frances Rebold, 1118 De Vere Drive,
Silver Spring, Md.

Filed July 19, 1961, Ser. No. 65,979

Term of patent 3½ years

(Cl. D34—4)

FIG. 1 is a front view of a stuffed doll, showing my new design.

FIG. 2 is a side view thereof.

FIG. 3 is a rear view of the stuffed doll.

I claim:

The ornamental design for a stuffed doll, substantially as shown.
